PUSH CART TYPE ICE RINK RESURFACING MACHINE

Jean Paul Leduc, Verdun, Montreal, Canada

Application October 20, 1955, Serial No. 541,697

3 Claims. (Cl. 37—13)

My invention relates to a push cart type ice rink resurfacing machine, and more particularly, to a compact, light weight, highly efficient ice resurfacing machine for ice skating rinks and the like.

One of the major problems that comes up in connection with the operation of ice skating rinks is the provision of a smooth ice skating surface. The blades of skaters' skates inherently dig into the ice rink surface, and every few hours the ice must be cleared of skaters for resurfacing same. This is ordinarily done by scraping or shaving the roughened ice surface in some manner, removing the shaved ice, and then spreading a thin film of water on the surface of the ice to fill in depressions and provide the new smooth surface.

A direct result of the increase in popularity of ice skating as a sport in recent years, and a corresponding increase in crowds at available ice rinks, has been a desire to mechanize as much as possible the steps of resurfacing the ice, so that this can be done with minimum loss of revenue producing time and as few attendants as possible. While a number of ice rink resurfacing machines have been proposed, they are in the main unsatisfactory for the reason that they are so complicated that their expense puts them out of reach of the average ice rink owner and are too large and heavy for travelling ice shows to transport from place to place. Moreover, they tend to be extremely heavy, thus endangering, if not damaging, undersurface facilities, and requiring a number of trained attendants to operate them.

The principal object of the present invention is to provide a light weight, compact, ice rink resurfacing machine that may be efficiently operated by one attendant, which may be so inexpensively manufactured that it is within reach of all ice rink owners, and which is small and compact enough to permit travelling ice shows to take the machine with them.

A further object of the invention is to provide an ice resurfacing machine including an improved rotatable cutter head and providing improved means for adjusting the blades of the cutter head with respect to the ice surface.

Another object of the invention is to provide an improved retractable roller device for use in raising and lowering the machine cutter head to and from the ice surface being treated.

Still another object of the invention is to provide an ice rink resurfacing machine that will readily resurface ice at the edge of the rink.

In accordance with the illustrated embodiment of the invention, I provide a push cart type of ice resurfacing machine comprising a relatively flat platform or frame provided at its rear end with a push cart type of handle. Adjustable roller means supports the front end of the platform, and retractable roller means is mounted inter-

2

mediate the front and rear end thereof for raising the machine from the surface of the ice before and after the resurfacing operation and for lowering the machine to the ice for the resurfacing operation. A main transversely extending, horizontally disposed, cutter head is rotatably secured to the platform underneath same adjacent the front end thereof and between the two roller means. A supplementary cutter head extends outwardly of one side of the platform. The platform preferably carries the power means for actuating the cutter heads and has secured thereto plow or scraper blade means for removing the cut ice, and a water distribution means that receives water from a receptacle also carried by the platform, said water distribution means being arranged to insure that a smooth skating surface is provided.

The machine may be operated by one attendant, who, after actuating the cutter heads and retracting the retractable roller device to lower the cutter heads into contact with the ice, pushes the machine along as one would operate a push cart. Preferably, the cutter heads are rotated so that the blades thereof tend to pull the machine along over the ice as they cut it, thus materially lessening the effort required by the operator.

Other objects, uses, and advantages will be obvious or become apparent after a perusal of the following description and the drawings.

In the drawings:

Figure 1 is a side elevational view of a preferred embodiment of the invention showing the machine in resurfacing position, the cutter heads being omitted for clarity of illustration;

Figure 2 is a plan view of the machine shown in Figure 1;

Figure 3 is a detail of the upper right hand corner of the machine as shown in Figure 2;

Figure 4 is front end elevational view of the machine of Figure 1;

Figure 5 is a cross sectional view along line 5—5 of Figure 4;

Figure 6 is similar to Figure 5, but is a fragmental view illustrating the operation of the retractable roller device employed in my invention;

Figure 7 is a cross sectional view along line 7—7 of Figure 5; and

Figure 8 is an enlargement of the cutter head and adjacent structure shown in Figure 5.

Referring first to Figures 1, 2 and 4, reference numeral 10 generally indicates the preferred embodiment of my invention comprising a relatively flat platform or frame 12 supported at its front end by adjustable roller means 14 and carrying runner means 16 that extend a substantial portion of its length. The power means 18 carried on the platform operates a rotatable cutting means 20. The platform 12 including the cutting means and runner means are raised and lowered from and to the ice surface by a retractable roller device 22 operated from the push cart type handle 24 secured to the rear end of the machine. The machine also includes a plow element 26 for moving the cut ice, known as "snow," to one side of the machine, and a water distribution unit 28. A receptacle means 32 is carried by the platform for supplying water to the water distribution unit 28.

The platform or frame 12 generally comprises a pair of vertically disposed plates 34 secured together in spaced apart relation by a plurality of planks or boards 36 bolted or otherwise secured thereto. Alternately, marine plywood would be satisfactory. Runners 38 are fixed to

the undersurface of the platform or frame by suitable elements 40 (see Figure 4). A beam 42 (see Figure 4) is secured to the front end of the platform or frame by bolts 44 passing through slots 46 formed in the beam ends into the angled ends 48 of the side plates 34. Washers 50 may be interposed between the heads of bolts 44 and the beam ends. The beam ends are preferably not tightly secured to the side plates 34, but rather are secured for sliding vertical movement with respect thereto.

Adjacent each end of the beam 42, a roller means 14 is mounted, each comprising in the illustrated embodiment a U-shaped member 52 having a roller 54 journalled between the arms 56 thereof and a screw threaded hole 58 formed in the web 60 thereof. The members 52 are welded to the beam 42 as at 62 and a screw threaded end of a rod 64 rotatably mounted on the platform in bearings 66 is received in the holes 58 of the members 52. Each rod 64 has an annular gripping hand wheel 68 keyed to the upwardly extending end thereof.

Just below one of the boards 36 a rod or shaft 70 (see Figures 1, 5 and 6) is rotatably mounted between the plates 34 in any suitable manner. Arms or levers 72 are welded to each end of the rod 70 at one end of each and adjacent the arm or lever 72 on the left hand side of the machine an arm or lever 74 is fixed to rod or shaft 70 in a similar manner. A plate 76 is fixed to each side plate 34 below the shaft or rod 70, in the manner indicated in Figure 7, wherein a plate 76 is shown welded to a block element 78 in turn welded to the adjacent plate 34. Each plate 76 is formed with a pair of vertical slots 80 and 82 into each of which extends a bolt 84 fixed to the retractable roller means 86 of retractable roller device 22. The retractable roller means 86 comprises a U-shaped element 88 having a roller 90 journalled between the legs 92 thereof, the roller 90 being mounted on the lower bolt 84 in the present embodiment. An upright bar or rod 94 is welded to the web 95 of the element 88, the upper end of which is pivotally connected to the outwardly projecting end of arm 72 by pin 96. The outwardly extending end of the arm 74 is pivotally connected to the link 98 that extends to the rear of the platform and is in turn pivotally connected to link 100 that extends substantially parallel to the handle 24. A link 101 may pivot the pivotal connection of links 98 and 100 to the platform 12.

The handle 24 generally compresses a pair of spaced apart angle bars 102, fixed at their lower ends to the side plates 34, having a hand gripping rod 104 (see Figure 2) fixed between their upper ends. A plate 106 (see Figure 1) is fixed to the bar 102 on the same side that the link 98 is on (the left hand side in the illustrated embodiment), a lever 108 being pivoted intermediate its ends to the plate by a pin 110. The upwardly extending end of the link 100 is pivotally connected to the upwardly projecting end 112 of the lever 108 and a pawl 116 biased by a suitable spring 118 cooperates with the ratchet teeth 120 formed on the curved portion of plate 106 to provide a releasable latching device for the retractable roller device. Hand lever 119 pivoted at 121 to lever 108 and connected to pawl 116 by links 123 is provided for ease in operating the pawl.

As shown more particularly in Figures 1, 2 and 3 the plow element 26, comprising a plow or scraper blade 124, and a water distribution unit 28 are mounted at the rear of the machine in that order outwardly from the platform. In the illustrated embodiment, the plow blade 124 is pivoted to the rearwardly extending center bar 130 by a bolt 132 (see Figure 2) welded to the plow and extending through this plate and at each end one hinge wing 134 is welded to the plow. An elongate plate 122, comprising a hinge wing, is fixed to each plate 34, a hinge wing 134 meshing with a hinge wing 122 when the plow blade is inclined as shown to receive a bolt 136 to secure the blade in this position. By removing bolt 136 and pivoting the plow blade 124 about bolt 132, the other

wings 122 and 134 may be brought into meshing engagement to receive the bolt 136. A suitably sized receptacle, such as the fifty gallon drum 172, comprises the receptacle means 32 and is mounted on the upper surface of the platform alongside power means 18. Conduit means, generally indicated at 174, including suitable valve 176, connects the receptacle with the hollow horizontal conduit 142 of water distribution means 28, the conduit 142 being formed along its lower edges with a plurality of small holes through which water passes onto the ice, and is smoothed out by the strip of duck canvas 144.

A suitable electric motor 148, operated by a switch 149, or other power unit, is mounted on the upper surface of platform or frame 12 for actuating the rotatable cutting means 20. Referring to Figures 1, 4, 5 and 8, the cutting means comprises cutter head 150 having, for instance, a pair of cutting blades 152 (four may also be employed) mounted in recesses 154 formed thereon. The respective blades 152 are secured to the cutter head by bolts 158 positioned in slots 156 formed therein and screwed into suitable holes formed in the cutter head. Suitable washers 159 may be employed if desired. Set screws 160 may be provided for adjusting the amount the sharp edge of each blade protrudes from the cutter head. The cutter head 150 includes a stub shaft 162 at each end thereof which are respectively mounted in suitable bearings 164 mounted in the side plates 34. One of the stub shafts extends outwardly of a bearing 164, and has keyed thereto suitable pulleys 166 adapted to be engaged by pulley belts 168 powered by the motor 148. The motor 148 is preferably actuated by connecting the end of the electrical conduit 170 to a suitable battery carried on the platform or to an electrical outlet (not shown) of the type that is normally found in the ceilings of enclosed ice rinks. If desired, a small gasoline engine can be substituted for the motor 148.

A shaft 180 is journalled in bearings 182 fixed to the members 40, and is positioned rearwardly of cutter head 150. On the right hand side of the machine this shaft extends outwardly to a pulley 184 powered by pulley belts 168. On the other side of the machine this shaft extends outwardly to a short cutter head 186, similar in form to cutter head 150, that protrudes beyond the left side of the platform somewhat as shown in Figures 2 and 4 for a purpose hereinafter made clear. A suitable framework 188 journalling the outer end of cutter head 184 may be provided to hold this cutter head from undesirable sidewise movement and protect it from obstructions.

Before the machine 10 is put into operation, the receptacle 172 is filled with water, and the conduit 170 connected to a source of electrical energy. The retractable roller device, which, when the machine is not in use is normally in the extended position, so that the machine may be wheeled about, is operated by moving the lever 108 to the full line position shown in Figure 1 to retract the rollers 90. The runners 38 and the adjustable rollers 54 will then support the platform or frame with the cutter head 150 positioned closely adjacent the surface of the ice. By turning the annular hand wheels 68, the depth of cut of the blades 152 may be varied. The angled ends 48 of plates 34 may be provided with suitable indicia as at 190 to aid in positioning the cutter head for the desired cut.

The motor 148 should be turned on before the rollers 90 are retracted and it rotates the cutter head 150 in the direction of the arrows of Figure 8. It will be noted that this direction is such that the blades 152 are drawn from front to rear when they are in contact with the ice, and move from the rear forwardly when they are above the ice, with the result that the cutter head tends to pull the machine along the ice as it cuts. It will be appreciated that this materially cuts down, if not entirely eliminating, the effort required by the attendant to move the machine. The valve 176 should be opened to permit

water to drain from the drum 172 to the water distribution unit 28. The operator then moves the machine across the surface of the ice by pushing against the handle bar 104 in much the same way that he would push a hand cart.

As the operator moves the machine across the ice, the cutter blade cuts down the surface thereof a moderate depth, no more than $\frac{3}{8}$ inch in the illustrated embodiment. The blade 124 catches the "snow" produced by this cutting operation and deflects it to one side of the machine where it may be picked up by another attendant following along behind. The water leaves the conduit 142 and passes onto the surface of the ice, to be wiped into a smooth level surface by the fabric strip 144.

By positioning the cutter head 186 adjacent the rink boards normally defining the edge of the rink, the ice surface can be resurfaced right up to the edge of the rink. In so doing, the operator merely runs the machine around the periphery of the rink with cutter head 186 positioned as closely as possible to the rink boards. Framework 188 protects the cutter head 186 from contact with the rink boards and insures that it will not be jarred out of axial alignment. It will be noted that cutter heads 150 and 186 are both automatically adjusted for proper depth of cut by turning hand wheels 68.

After use, the retractable roller 90 may be extended by moving the lever clockwise (as seen in Figure 1). The machine then may be wheeled off of the ice and into the place of storage.

One of the novel features of my machine is that it will level the surface of the ice relatively close to the side boards or ring normally defining the edge of a rink. As is well known in this art, the surface of the ice tends to build up around the outer periphery of the rink. However, by properly adjusting the level of beam 42, the level of the ice obtained at the center of the rink may be extended close to the sides thereof.

The illustrated embodiment of the invention stands thirty-two inches in height, is thirty-six inches wide, forty-five inches in length and weighs only five hundred pounds. The cutter head 150 cuts a swathe thirty-two inches wide. The compactness and light weight of the device make it unusually easy to handle, and since it is so easily operated, skilled operators are not required. Only one operator is needed to operate the machine, with one or more attendants following to take up the "snow" formed by the cutter head. I contemplate that means may be provided for taking up this snow and melting it to provide water for the receptacle. However, to preserve lightness of weight, compactness, and portability, I prefer not to employ such means on the illustrated embodiment.

It will be appreciated that my machine may be made from few and simple elements that are inexpensively obtained and assembled. The inexpensiveness of my machine, in addition to its compactness and lightness in weight, puts it in reach of small ice skating rink owners and ice shows financially, who heretofore could not afford to buy and ship from place to place the relatively large and heavy conventional resurfacing machines.

The foregoing description and the drawings are given merely to explain and illustrate my invention, and the manner in which it may be performed, and the invention is not to be limited thereto, except insofar as the appended claims are so limited since those skilled in the art who have my disclosure before them will be able to make modifications and variations therein without departing from the scope of the invention.

I claim:

1. An ice rink resurfacing machine comprising a relatively flat platform having front and rear ends, a beam mounted on said platform at the front end thereof for limited vertical movement, roller means secured to each end of said beam, said roller means being adapted to engage the surface of the ice, screw threaded means for

vertically adjusting each end of said beam, further roller means secured to said platform intermediate the front and rear ends thereof, said further roller means being retractably mounted, runner means secured to said platform between said further roller means and the rear end of said platform, means for retracting said further roller means to permit said runner means to engage the ice, and a cutter head rotatably mounted on said platform adjacent the first mentioned roller means and adapted to be positioned adjacent the surface of the ice, said cutter head including at least one cutting blade, and means for rotating said cutter head, said cutter head being rotated in a direction to draw said cutting blade from front to rear as it engages the ice.

2. An ice rink resurfacing machine comprising a relatively flat platform having front and rear ends, a push cart type handle secured to said rear end of said platform, a beam mounted on said platform at the front end thereof for limited vertical movement with respect to the platform, roller means secured to each end of said beam, said front end of said platform being supported on said roller means, means for vertically adjusting each end of said beam, further roller means secured to said platform intermediate the front and rear ends thereof, longitudinally extending runner means secured to said platform between said further roller means and the rear end of said platform, said further roller means comprising a retractable roller device for supporting the rear end of the platform which when said device is extended, said platform being supported by said runner means when said device is retracted, said retractable roller device comprising a generally horizontal shaft rotatably secured to said platform, an elongate vertical plate secured to said platform adjacent said shaft, wheel means positioned adjacent said plate, said wheel means including a roller, means slidably securing said wheel means to said plate for vertical movement with respect thereto, a first arm keyed to said shaft at one end thereof and secured to said wheel means at the other end thereof, a second arm keyed to said shaft, a lever pivotally mounted on said handle intermediate the ends of said lever, linkage means extending between and connecting one end of said lever and said second arm, releasable latch means for releasably locking said further roller means in extended position, a horizontally disposed cutter head rotatably mounted at the front end of said platform between the first mentioned roller means and said further roller means, said cutter head including at least one transversely extending blade adapted to engage the ice, means for rotating said cutter head, said cutter head being rotated in a direction to draw said cutting blade from front to rear as the blade engages the ice, a plow blade secured to said platform adjacent the rear end thereof, water distribution means secured to said platform adjacent the rear end thereof, said water distribution means being positioned outwardly of said blade, a liquid receptacle mounted on said platform, and conduit means connecting said receptacle with said distribution means.

3. An ice rink resurfacing machine comprising a relatively flat platform having front and rear ends and a relatively low center of gravity, upwardly extending handle means secured to the rear end of said platform, first roller means supporting said front end of said platform, second roller means being secured to said platform intermediate the front and rear ends thereof, said second roller means being retractably mounted, runner means secured to said platform between said second roller means and the rear end of said platform, means for retracting said second roller means to permit said runner means to engage the ice, a rotatable cutting means secured to said platform between said first and second roller means and extending crosswise of the platform, said cutting means including at least one cutting blade, means for rotating said cutting means, said cutting means being rotated in a direction to draw said cutting blade from front to rear as it engages

the ice, a transversely extending plow blade secured to said platform adjacent the rear end thereof and under said handle means, water distribution means secured to said platform outwardly of said blade, means for supplying water to said water distribution means including a water receptacle mounted on said platform, and supplemental cutting means secured to said platform adjacent the first mentioned cutting means and between said first and second roller means, said supplemental cutting means extending outwardly of one side of said platform.
